UNITED STATES PATENT OFFICE.

ALFRED N. GOLDSMITH, OF NEW YORK, N. Y., ASSIGNOR TO GENERAL ELECTRIC COMPANY, A CORPORATION OF NEW YORK.

RADIOSIGNALING SYSTEM.

1,347,328.

Specification of Letters Patent. Patented July 20, 1920.

Application filed March 29, 1917. Serial No. 158,218.

To all whom it may concern:

Be it known that I, ALFRED N. GOLDSMITH, a citizen of the United States, residing at New York, in the county of New York, State 5 of New York, have invented certain new and useful Improvements in Radiosignaling Systems, of which the following is a specification.

My present invention relates to the production of radio frequency continuous electrical oscillations for use in a signaling system, and to means for controlling the amplitude of such oscillations in accordance with the variations in the amplitude of a signaling current such, for example, as a current produced by sound waves.

It has been found that an electron discharge device of the type known as "pliotron" consisting of a filamentary electron 20 emitting cathode, an anode and a discharge controlling grid inclosed in an envelop evacuated to such a degree that the device is operatively independent of positive gas ionization at voltages above this ionization 25 voltage characteristic of whatever residual gas remains within the envelop, may be utilized to advantage for the production of radio frequency continuous oscillations. Devices of this type have been described by Dr. Irving Langmuir in a paper published in the "Proceedings of the Institute of Radio Engineers" of September, 1915. In order to utilize such oscillations for radio signaling and particularly for radio telephony, it is 30 necessary to modulate or vary the amplitude of the oscillations supplied to the radiating system in accordance with variations in the signaling current. A pliotron may also be used to advantage as an amplifier of variable 35 currents since by reason of its property of being operable at high voltages the energy output which may be obtained from a single device is much greater than that obtainable from previously known electron discharge 40 devices in which gas ionization takes place and affects the operation even at low voltages. One of the objects of my invention is to provide an improved system in which pliotrons are used for supplying modulated 45 radio frequency currents to a radiating system.

A further object of my invention is to provide a circuit arrangement in which a single source of energy may be utilized for

supplying the operating current or potential 55 for a plurality of pliotrons which are used for different purposes.

In carrying my invention into effect I utilize an electron discharge device, which is preferably a pliotron, for producing radio 60 frequency oscillations, I impress an oscillating potential obtained from this oscillator upon the secondary of a transformer which is connected to the grid circuits of a plurality of pliotrons connected in parallel in 65 order to produce an amplified radio frequency current which will supply the desired amount of energy for the operation of the radiating system. The radio frequency potential which is supplied to the grid circuits of the amplifiers is modulated by means of another pliotron whose plate circuit includes the transformer secondary. The resistance of the modulating pliotron is varied by varying the potential of its grid in accordance with variations in the signaling 70 current. As the resistance of the modulating pliotron is varied a variable amount of current is caused to flow therethrough from the transformer secondary and the potential 75 across the secondary is varied accordingly. As a result the current output of the amplifiers will vary in accordance with the variations in the signaling current. In order that a single source of current may be utilized 80 for heating a number of filaments of the different pliotrons I arrange the system in such a way that one terminal of each such filament is at earth potential. This arrangement also enables me to utilize a single 85 source of energy for supplying the operating current for the oscillators and for the power amplifiers.

The novel features which I believe to be characteristic of my invention are set forth 95 with particularity in the appended claims. The invention itself, however, both as to its organization and method of operation, together with further objects and advantages thereof will best be understood by reference 100 to the following description taken in connection with the accompanying drawing in which I have indicated diagrammatically one way in which my invention may be carried into effect.

The pliotron 1 comprising the usual filamentary cathode 2, anode 3 and grid 4 inclosed in an evacuated envelop is employed

for producing radio frequency oscillations, and I term this the "master oscillator". The anode and grid of the master oscillator are connected to a circuit which comprises 5 an inductance 5 and a variable condenser 6 by means of which the circuit is tuned to the frequency of the oscillations which are to be produced. Energy for the operation of the master oscillator is supplied to 10 the plate circuit by the direct current generator 7 which is connected to the cathode and anode, the cathode being grounded at 8. Condenser 9 prevents the direct current component of the plate current from flowing 15 through inductance 5. An inductance 10 in series with the generator 7 and a condenser 11 in parallel therewith serve to smooth out any irregularities in the current supply and a choke coil 12 which I term a "radio frequency choke coil" prevents the radio frequency component of the plate current from flowing through the generator 7. It has been customary heretofore to regard any 20 large inductance as a choke coil for radio frequency currents. All inductances however have distributed capacity between the turns which may be considered as a condenser in parallel with the inductance. This capacity will serve to by-pass a considerable amount of radio frequency energy 25 unless the capacity is such that the natural period of the coil resulting from its inductance and capacity is approximately equal to that of the frequency which is to be choked out. If the coil is so designed, it 30 will act as a high impedance to the desired radio frequency currents and by the term "radio frequency choke coil" I mean a coil which is designed to offer a high impedance 35 of this sort to the radio frequency currents 40 of which will tend to flow in the circuit in which it is employed.

The cathode 2 of the master oscillator is connected to a point 13 in the inductance 5 which point may be varied as desired in order to obtain the most efficient operation of the system. It will usually be found desirable to apply to the grid a definite potential with respect to the filament in order 45 to adjust the normal current through the pliotron to a point on its operating characteristic which will be most favorable for its operation. This potential, which will usually be negative, may be obtained from 50 the battery 14, a radio frequency choke coil 55 being included in the circuit to prevent radio frequency currents from flowing through the battery 14. The condenser 16 will prevent the short circuiting of battery 60 14 through inductance 5. The direct current generator 17 with an inductance 18 in series therewith furnishes current for heating the cathode of the master oscillator and also for the cathodes of the other pliotrons as 65 indicated. While the circuit which I have

described above for producing oscillations is the one which I prefer other circuit arrangements may be used without departing from the scope of my invention.

The inductance 5 forms the primary of 70 a radio frequency transformer, one end of the secondary 19 of which is connected to the cathodes of a series of amplifying pliotrons 20, 21, 22, which are all connected in multiple. While I have indicated only 75 three pliotrons thus connected, as many may be used in this way as desired or as may be necessary to secure the desired output in the radiating system. A suitably selected point 23 in the secondary 19 is connected to 80 the grids of the amplifiers through a condenser 24 and a resistance 25. The grids of these amplifiers are maintained at a definite potential with respect to the cathodes by means of the battery 14, a radio frequency choke coil 26 in series therewith preventing radio frequency currents from flowing through the battery and the condenser 24 preventing the short circuiting of the 85 battery through secondary 19 of the transformer. Without the resistance 25 there is a tendency for the amplifiers to oscillate at 90 an audio frequency or to oscillate at radio frequency because of the internal capacity coupling of the pliotrons between the electrodes. The resistance 25, however, effectively prevents the setting up of these 95 undesirable oscillations.

The generator 7 furnishes current for the 100 operation of the plate circuits of the amplifiers and the anodes of the amplifiers in the present case are connected through a condenser 27 and a variable contact 28 to inductance 29 which is included in circuit with the antenna 30. By connecting the 105 plate circuit of the amplifiers to the antenna in this way a definite best impedance may be secured as a load on the amplifiers. It has been found that the amplifiers operate most 110 efficiently when the impedance of the load circuit has a particular value, this value depending upon the characteristics of the amplifiers. Since the antenna system as a 115 whole may not have the desired impedance I include in the load circuit only enough 120 of the antenna impedance to give the desired value. It will of course be apparent that the output of the amplifiers may be supplied to other load circuits than an antenna if desired.

The output of the amplifiers is a function 125 of the voltage impressed upon their grids from the transformer secondary 19, this voltage being due to the alternating current of radio frequency produced in inductance 5. If the transformer secondary 19 be shunted by a variable resistance the voltage across it will vary as a function of the value of the resistance. For a very high resistance 130 the voltage will be practically the same as

for an open circuit and the output of the amplifier will be a maximum. For a short circuit the input voltage and high frequency output of the amplifier will both be zero.

5 For intermediate values of resistance the amplifier output will depend upon the particular value of the resistance.

In the present case I employ a pliotron 31, as a variable resistance shunt to the 10 transformer secondary 19, the resistance of the pliotron between cathode and anode being a function of its grid voltage. When this voltage is highly negative with respect to the cathode the resistance is very high, as 15 the grid voltage is made less negative or even positive the resistance becomes corresponding smaller. A definite operating potential may be supplied to the grid of pliotron 31 by means of the connection 32 20 to battery 14 through the radio frequency choke coil 33. This pliotron I term the "modulator". While the pliotron is the preferred form of modulator, other forms of controllable absorbing elements may be 25 adapted for the desired purpose.

In the system illustrated the potential of the modulator grid is varied in accordance with variations in a telephone current produced by the telephone transmitter 34 which 30 is included in a local circuit with battery 35 and the primary 36 of an audio frequency transformer. The telephone current thus produced is amplified by impressing the potential of the transformer secondary 37 upon 35 the grid of a pliotron amplifier 38. Current for the operation of this amplifier is derived from the battery 14 through the connection 39. The plate circuit of amplifier 38 includes the primary 40 of a transformer the 40 secondary 41 of which is in circuit with the grid of modulator 31. The grid of amplifier 38 is given a definite operating potential by means of the battery 42. By this arrangement the potential of the grid of modulator 45 31 is made to vary in accordance with variations in the telephone current. The resistance of the modulator and hence the radio frequency potential applied to the grids of the amplifiers and the output of the amplifiers are, as a result, all varied in accordance 50 with the variations in the telephone current. Radio frequency choke coil 43 prevents the alternating component of the amplifier current from flowing through generator 7.

55 It will be noted that the modulator is connected across all of transformer secondary 19 while only a portion of secondary 19 is connected in the grid circuits of the amplifiers. This arrangement may be reversed if 60 desired or both connections may be made to the same point in secondary 19. The object of varying the points of connection is to secure the most efficient operating voltages for the modulator plate circuit and the amplifier grid circuits. It will usually be

found desirable to connect the circuits in the manner indicated, as by this connection the modulator plate circuit will operate at a higher voltage than that applied to the amplifier grids and this condition will be most 70 suitable for efficient operation.

While I have described a system for producing radio frequency currents which are modulated in accordance with variations in a locally produced telephone current, my invention is by no means limited in its usefulness to this particular purpose. It will be apparent that the telephone current employed may equally well be one which is derived from a long distance line through 75 one or more line amplifiers such as 38. It will also be apparent that the system may be utilized for radio telegraphy by varying the modulator grid potential in accordance with variations in a telegraphic current. I 80 have also described the electron discharge devices used as pliotrons since by reason of the ability of such devices to operate at high voltages, their use is preferable whenever it is desired to control more than a few 85 watts of electrical energy. It will be apparent, however, that in so far as the principle of operation is concerned other devices in which gas ionization or conduction plays a part in the operation may be equivalents 90 of pliotrons.

What I claim as new and desire to secure by Letters Patent of the United States is:

1. The combination in a radio signaling system of a pliotron oscillator having a resonant circuit associated with its anode and grid and so arranged that radio frequency oscillations will be produced in an inductance included in said resonant circuit, a second inductance coupled to the first mentioned inductance and connected to the grid circuits of a plurality of pliotron amplifiers connected in parallel, a pliotron modulator having its cathode and anode connected to said second inductance, means for producing 100 a current by sound waves, a pliotron amplifier for amplifying the current thus produced and for varying the grid potential of said pliotron modulator in accordance with variations in the amplified current, a common direct current source of potential for supplying energy to the plate circuits of said pliotron oscillator and said first mentioned amplifiers, a common direct current source of potential for fixing the normal potential of the grids of said oscillator, first mentioned amplifiers and modulator, and supplying current to the plate circuit of the second mentioned amplifier, radio frequency choke coils for preventing radio frequency 110 currents from flowing through said direct current sources and a direct connection between the plate circuits of the amplifiers and a radiating antenna, said connection being variable in order to adjust the impedance 115 120 125 130

in the load circuit of the amplifiers to a value suitable for the most efficient operation of the system.

2. The combination in a radio signaling system of a pliotron oscillator having a resonant circuit associated with its anode and grid and so arranged that radio frequency oscillations will be produced in an inductance included in said resonant circuit, a second inductance coupled to the first mentioned inductance and connected to the grid circuits of a plurality of pliotron amplifiers connected in parallel, a pliotron modulator having its cathode and anode connected to 70 said second inductance, means for varying the grid potential of said pliotron modulator in accordance with variations in a current produced by sound waves, a common direct current source of potential for supplying energy to the plate circuits of said pliotron oscillator and said amplifiers, a common direct current source of potential for fixing the normal potential of the grids of said oscillator, amplifiers and modulator, 80 radio frequency choke coils for preventing radio frequency currents from flowing through said direct current sources and a direct connection between the plate circuits of the amplifiers and a radiating antenna, 85 said connection being variable in order to adjust the impedance in the load circuit of the amplifiers to a value suitable for the most efficient operation of the system.
3. The combination in a radio signaling system of means for producing radio frequency oscillations and supplying them to an inductance in the grid circuits of a plurality of pliotron amplifiers connected in parallel, a pliotron modulator having its 90 cathode and anode connected to said inductance, means for varying the grid potential of said modulator in accordance with variations in a signaling current, a common direct current source of potential for fixing the normal potential of the grids of said amplifiers and modulator, radio frequency choke coils for preventing radio frequency currents from flowing through said direct current source, and a direct connection between the plate circuits of the amplifiers and a radiating antenna, 95 said connection being variable in order to adjust the impedance in the load circuit of the amplifiers to a value suitable for the most efficient operation of the system.

4. The combination in a radio signaling system of a pliotron oscillator having a resonant circuit associated therewith and so arranged that radio frequency oscillations will be produced in an inductance included 100 in said resonant circuit, a second inductance coupled to the first mentioned inductance and connected in the grid circuits of a plurality of pliotron amplifiers connected in parallel, a pliotron modulator having its cathode and anode connected to said second inductance, means for varying the grid potential of said modulating pliotron in accordance with variations in a signaling current, an earth connection to the cathodes of said oscillator, amplifiers and modulator, a common direct current source of potential for supplying energy to the plate circuits of said oscillator and said amplifier, and a common direct current source of potential for fixing the normal potential of the grids of said oscillator, amplifiers and modulator.

cathode and anode connected to said second inductance, means for applying to the cathode and anode of said modulator a different voltage than that applied to the grid circuits of the amplifiers, and means for 75 varying the grid potential of said modulator in accordance with variations in a signaling current.

5. The combination in a radio signaling system of a pliotron oscillator having a resonant circuit associated therewith and so arranged that radio frequency oscillations will be produced in an inductance included 80 in said resonant circuit, a second inductance coupled to the first mentioned inductance and connected in the grid circuits of a plurality of pliotron amplifiers connected in parallel, a pliotron modulator having its cathode and anode connected to said second inductance, means for varying the grid potential of said modulating pliotron in accordance with variations in a signaling current, an earth connection to the cathodes of said oscillator, amplifiers and modulator and a common direct current source of potential 85 for supplying energy to the plate circuits of said oscillator and said amplifier.

6. The combination in a radio signaling system of a pliotron oscillator having a resonant circuit associated therewith and so arranged that radio frequency oscillations will be produced in an inductance included in 90 said resonant circuit, a second inductance coupled to the first mentioned inductance and connected in the grid circuits of a plurality of pliotron amplifiers connected in parallel, a pliotron modulator having its cathode and anode connected to said second inductance, means for varying the grid potential of said modulator, in accordance with variations in a signaling current, an earth connection to the cathodes of said oscillator, amplifiers and modulator, a common direct current source of potential for supplying 95 energy to the plate circuits of said oscillator and said amplifier, and a common direct current source of potential for fixing the normal potential of the grids of said oscillator, amplifiers and modulator.

7. The combination in a radio signaling system of a pliotron oscillator having a resonant circuit associated therewith and so arranged that radio frequency oscillations will be produced in an inductance included 100 in said resonant circuit, a second inductance coupled to the first mentioned inductance and connected in the grid circuits of a plurality of pliotron amplifiers connected in parallel, a pliotron modulator having its cathode and anode connected to said second inductance, means for varying the grid potential of said modulating pliotron in accordance with variations in a signaling current, an earth connection to the cathodes of 105 said oscillator, amplifiers and modulator, a common direct current source of potential for supplying energy to the plate circuits of said oscillator and said amplifier, and a common direct current source of potential for fixing the normal potential of the grids of said oscillator, amplifiers and modulator.

8. The combination in a radio signaling system of a pliotron oscillator having a resonant circuit associated therewith and so arranged that radio frequency oscillations will be produced in an inductance included 110 in said resonant circuit, a second inductance coupled to the first mentioned inductance and connected in the grid circuits of a plurality of pliotron amplifiers connected in parallel, a pliotron modulator having its cathode and anode connected to said second inductance, means for varying the grid potential of said modulating pliotron in accordance with variations in a signaling current, an earth connection to the cathodes of 115 said oscillator, amplifiers and modulator, a common direct current source of potential for supplying energy to the plate circuits of said oscillator and said amplifier, and a common direct current source of potential for fixing the normal potential of the grids of said oscillator, amplifiers and modulator.

- common direct current source of potential for supplying energy to the plate circuits of said oscillator and said amplifier, a common direct current source of potential for fixing 5 the normal potential of the grids of said oscillator, amplifiers and modulators, and radio frequency choke coils for preventing radio frequency currents from flowing through said direct current sources.
- 10 8. The combination in a radio signaling system of means for producing radio frequency oscillations and supplying them to an inductance in the grid circuits of a plurality of pliotron amplifiers connected in 15 parallel, a pliotron modulator having its cathode and anode connected to said inductance, means for varying the grid potential of said modulator in accordance with variations in a signaling current, a common direct 20 current source of potential for fixing the normal potential of the grids of said amplifiers and modulator and radio frequency choke coils for preventing radio frequency currents from flowing through said direct 25 current source.
9. The combination in a radio signaling system of means for producing radio frequency oscillations and supplying them to an inductance in the grid circuits of a plurality 30 of pliotron amplifiers connected in parallel, a pliotron modulator having its cathode and anode connected to said inductance, means for varying the grid potential of said modulator in accordance with variations in a signaling current and a common direct current source of potential for fixing the normal 35 potential of the grids of said amplifiers and modulator.
10. The combination in a radio signaling 40 system of means for producing radio fre-

quency oscillations and supplying them to an inductance in the grid circuits of a plurality of pliotron amplifiers connected in parallel, a pliotron modulator having its cathode and anode connected to said inductance, means for varying the grid potential of said modulator in accordance with variations in a signaling current, an earth connection to the cathodes of said amplifiers and modulator and a common direct current 45 source of current for supplying heating current to the cathodes of said amplifiers and modulator. 50

11. The combination in a radio signaling system of means for producing radio frequency oscillations and supplying them to an inductance in the grid circuits of a plurality of pliotron amplifiers connected in parallel, a variable resistance device connected to said inductance, means for varying the resistance of said device in accordance with variations in a signaling current and means for applying to said variable resistance device a different voltage than that applied to the grid circuits of the amplifier. 55

12. The combination in a radio signaling system of an antenna and a plurality of pliotron amplifiers arranged to supply modulated radio frequency currents to said antenna, the plate circuits of said amplifiers 60 being connected to said antenna by direct connections, and said connections being variable in order to adjust the impedance in the load circuit of the amplifiers to a value suitable for the most efficient operation of the 75 supply system.

In witness whereof, I have hereunto set my hand this 27th day of March, 1917.

ALFRED N. GOLDSMITH.
